UNITED STATES PATENT OFFICE.

PETER M. BROWN, OF CARROLLTON, ILLINOIS.

PORTABLE FENCE.

Specification of Letters Patent No. 26,413, dated December 13, 1859.

To all whom it may concern:

Be it known that I, PETER M. BROWN, of Carrollton, in the county of Greene and State of Illinois, have invented a new and 5 Improved Portable Fence; and I do hereby declare that the following is a full and exact description thereof, reference being had to the accompanying drawings, making a part of this specification.

10 Figure 1, is a side view of one entire section of my improved fence, represented as combined with a post and with a portion of another section of the fence. Fig. 2, is an end view of said fence; and Figs. 3 and 4, 15 represent a modified form of a post which may be used for supporting the sections of my improved fence.

Similar letters indicate like parts in each of the drawings.

20 Each section of my improved fence is composed of a double series of oppositely inclined board-strips *a a'* and *b b'*, which are united to each other by means of a suitable number of pins *g g*, in such a manner 25 that the said section can be lengthened or shortened at pleasure; the said section diminishing in height as its length is increased, and vice versa. The manner of connecting the respective parts of the sections of my improved fence, also enables them to be condensed into an exceedingly 30 compact form for the purpose of facilitating their removal from place to place.

The foremost strips *a'* and *b'*, of each of 35 the series of inclined strips which compose a section of my improved fence, is a little shorter than the others, and is notched—as shown in the drawings—for the purpose of enabling the sections to be more conveniently 40 combined with their supporting posts and with the transverse base supporters *d d*, of said posts.

The posts *c*, which I employ for uniting and sustaining the respective sections of my 45 improved fence, have two mortises formed in each of them; which mortises are of such a length and breadth that the lower mortise

in each post will receive the united lower ends of the outermost strip of each of two united sections, while the upper mortise in 50 said post, receives the upper ends of the outermost strip of each of the oppositely inclining series of strips in said sections.

A transverse recess *h*, at the lower end of each fence post, receives a base-supporting 55 plank *d*, which is held in its place by means of the notch in the lower end of the section-strip *a'* or *b'*, which passes into the lower mortise in said post, and by the abutting end of the second strip in the opposite section which is united to that post, as represented in Fig. 1.

If preferred, the posts employed for uniting and supporting the sections of my improved fence, may be formed with recesses 65 *e e*, in their sides instead of mortises, which recesses may be covered by a hinged strip *f*, that may be secured by a key or pin at its lower end. The fence-posts may, or may not have pointed ends descending below 70 their respective base-supporters *d d*.

I am aware that the principle of constructing gates and the sections of fences, of a double series of oppositely inclining connected slats, is not new, and therefore 75

What I claim as my invention and desire to secure by Letters Patent, is—

Giving such a shape to the slats at each end of the sections of my improved fence, that the said sections can be securely interlocked with each other, by means of supporting posts of the within described shape, in such a manner that the said sections can be either lengthened or shortened, when they are put up for use, substantially as herein 85 set forth.

The above specification of my improved portable fence signed and witnessed this 31st day of October 1859.

PETER M. BROWN.
